UNITED STATES PATENT OFFICE.

HENRY A. SPEAR, OF EVERETT, MASSACHUSETTS.

GRATE.

SPECIFICATION forming part of Letters Patent No. 665,278, dated January 1, 1901.

Application filed April 5, 1900. Serial No. 11,744. (No model.)

To all whom it may concern:

Be it known that I, HENRY A. SPEAR, of Everett, in the county of Middlesex and State of Massachusetts, have invented certain new and useful Improvements in Grates, of which the following is a specification.

This invention has relation to grates for boiler-furnaces, it relating more particularly to that class of grates wherein provision is made for shaking the fuel-supporting bars or sections thereof. Usually in such grates a large number of castings are required for the formation of the parts composing the same, and this has been one of the serious disadvantages incident to the employment of such grates, occasioning, as it does, great inconvenience in repairing or renewing the worn-out parts thereof and entailing an increased cost of manufacture and renovation.

The primary object of the present invention is to simplify grates of the character referred to and at the same time provide a construction and arrangement of parts wherein the proper amount of oxygen-bearing atmosphere is admitted to all of the parts of the fire-bed to promote combustion and insure the economic consumption of the coal.

Referring to the drawings, which illustrate one embodiment of the present invention, Fig. 1 represents in plan view a grate constructed in accordance with my said invention. Fig. 2 represents a section through the same to illustrate the mechanism for rocking the grate-bars. Fig. 3 represents a longitudinal section on the line 3-3 of Fig. 1 looking in the direction of the arrow. Fig. 4 represents in side elevation one of the grate-bars. Fig. 5 represents the end or finger bar of the frame surrounding the rocking sections or grate-bars. Fig. 6 represents a detail perspective view of the interlocking ends of two of the bars, said figure representing said bars in solid lines as separated from each other, the dotted-line position of one of the bars indicating the relative positions of the two bars when set in position for use.

I have not illustrated a boiler-furnace, as it seems unnecessary so to do, in pointing out the features of my present invention; but it will be understood that my improved grate may be used in any pattern or type of boiler-furnace.

The front and rear walls of the fire-box (the rear wall not being shown and the front wall being indicated as *a* in Fig. 2) are each provided with an iron bar *b*, and upon these said bars rest the ends of longitudinal bars *c*. These said bars are preferably of cast metal, and they are arranged in pairs, as shown in Fig. 1, each pair being utilized to support a plurality of grate-bars. Said bars *c* have a straight upper edge and a curved lower edge, whereby they taper from the center to the ends, and they are provided with laterally-projecting fingers or ribs *c'*, arranged at suitable equal distances from each other. Thus the fingers or ribs project from one side only, and the bars are arranged with the fingers extending outward, so that the two intermediate bars when placed together have their fingers coincident, as shown in Fig. 1. When two sections comprising the longitudinal or side bars *c* and the end bars *h* are placed together, as shown in Fig. 1, the coinciding fingers or ribs *c'*, which project laterally from the adjacent bars *c*, form spaces between them for the passage of the proper amount of oxygen-bearing atmosphere, as hereinbefore stated. To support them between their ends, the outer bars are provided with lips *c''*, which project into spaces left in the brick walls at the sides of the fire-box, while the two inner bars are not provided with these lips, but are apertured to receive bolts *c'''*, (see Fig. 3,) and a supporting rod or strut *c''''* is passed under said bolts and is bent at its ends over the iron bars *b*, whereby said intermediate bars are likewise supported between their ends. The tops of the said longitudinal bars are recessed, as at *c⁵*, to form bearings for the trunnions *d* of the rocking grate-bars *d*. Said grate-bars are quadrangular in plan view, being oblong in shape and provided with parallel bars *d²*, connected at intervals, as at *d³*. These grate-bars *d* are supported upon the longitudinal bars *c* at points far enough apart to permit them to rock without interfering with each other. They may be as many in number as may be desired, although I usually employ from six to eight, this depending, of course, upon the size of the fire chamber or box.

Each of the grate-bars is provided at one end with a downwardly-projecting arm *d⁴*,

and said arms are all pivotally connected by studs d^3 with a rocking bar f , which projects through an aperture in the front wall a and is pivotally connected to a lever g , whose lower 5 end is connected by a stud g' with a link g^2 , pivoted at g^3 to a bracket g^4 , supported upon the front face of the wall a . The lever g is provided with a handle or with means by which it may be rocked about its fulcrum for 10 the purpose of swinging the grate-bars about the axes of their trunnions. The two sets of grate-bars are independent of each other, each being provided with a shaking bar f .

At the front and rear ends of the grate there 15 are cross-bars h , which are provided along one side with lateral fingers h^2 . These bars may be so arranged that their fingers project inward toward the front and rear side of the grate-bars, or else said fingers may project 20 outward. At their ends said cross-bars are provided with flanges or ribs h^2 , which project into rabbeted portions of the longitudinal bars c , said last-mentioned bars being likewise provided with lips c^6 , which take under 25 the lower edges of the said cross-bars, as indicated in Fig. 6.

Thus it will be seen that the grate is practically formed in two sections, divisible along the median line, said sections being duplicates of each other. Each section consists 30 of the side bars c and the end bars h , which form a frame to inclose the rocking grate-bars d . There may be as many of these sections as are necessary, and instead of having two, as I have shown, there may be three, four, or more. Each section requires but three sets of castings—to wit, the grate-bars, the side bars, and the end or cross bars. The side bars are firmly braced and held against 35 lateral movement at their ends by the cross-bars, which latter are held against inward movement or movement toward each other by the rabbeted portions at the ends of the side bars c . It will thus be understood that 40 a grate-surface of any desired extent may be built up by means of the sections composed of the bars described, with little or no interference with the proper supply of oxygen-bearing atmosphere by the bars which define 45 the edges of each section, this being due to the provision of the spaces between the coinciding laterally and outwardly projecting fingers c' .

By the provision of oblong grate-bars which 50 are arranged to tilt or rock on trunnions at their ends the fire may be dumped into the ash-pit with little trouble instead of drawing it through the door, as ordinarily. This 55 not only avoids the free dissemination of

dust from the ashes, but permits retaining 60 the steam at a uniform pressure.

Having thus explained the nature of the invention and described a way of constructing and using the same, although without attempting to set forth all of the forms in 65 which it may be made or all of the modes of its use, I declare that what I claim is—

1. A grate comprising rocking grate-bars, side bars in which said rocking grate-bars are trunnioned, said side bars being provided 70 with laterally and outwardly projecting fingers or ribs, and end or cross bars which brace and separate the ends of the said side bars, said cross or end bars being provided with laterally-projecting fingers or ribs, the 75 fingers or ribs of the adjacent side bars coinciding with each other to form air-spaces, substantially as described.

2. A grate comprising a plurality of similar sections, each section consisting of side 80 bars supported at their ends, independent end bars separating and bracing the ends of the side bars, and rocking grate-bars trunnioned upon the said side bars, said end and side bars being provided with laterally-projecting ribs or fingers, the fingers or ribs of the adjacent side bars coinciding with each other to form air-spaces, substantially as described.

3. A grate comprising side bars supported 90 at their ends, said ends being rabbeted, end bars having lips or flanges projecting into the rabbeted portions at the ends of the side bars, said side bars being also provided with lips or ribs to take under the ends of the end 95 bars, and rocking grate-bars trunnioned in the said side bars and occupying the space between the end bars, the side bars having laterally and outwardly projecting fingers or ribs coinciding with each other to form air-spaces between the adjacent side bars, substantially as described.

4. A grate comprising a plurality of rocking grate-bars, independent end bars, and side bars, said side and end bars being locked 105 together at their ends, and said side bars being supported between their ends, the side bars having laterally and outwardly projecting fingers or ribs coinciding with each other to form air-spaces between the adjacent side 110 bars, substantially as described.

In testimony whereof I have affixed my signature in presence of two witnesses.

HENRY A. SPEAR.
